UNITED STATES PATENT OFFICE.

ROBERT MINSHULL, OF WATERLOO, WISCONSIN.

STANCHION LOCK.

Application filed May 27, 1921. Serial No. 472,953.

To all whom it may concern:

Be it known that I, Robert Minshull, a citizen of the United States, and resident of Waterloo, in the county of Jefferson and 5 State of Wisconsin, have invented new and useful Improvements in Stanchion Locks, of which the following is a description, reference being had to the accompanying drawings, which are a part of this specification. 10 This invention relates to stanchion locks particularly to that type of stanchion which in combination with an upper substantially horizontally relatively fixed member is provided with two vertical members, one of 15 which is fixed and the other of which is pivotally connected at the bottom and adapted to swing laterally into open and closed position.

The primary object of this invention is to 20 provide a lock for the swinging member of simple and strong construction which will operate automatically to lock the swinging member in its closed position when the latter is moved thereto and which, furthermore, 25 will reliably and effectively maintain said swinging member in its locked position against the strains set up in the stanchion members by the animal rubbing and pushing thereagainst.

30 A further object of the invention is to provide a lock which may be conveniently released from either side of the stanchion.

The invention consists in the novel constructions, arrangements and devices to be 35 hereinafter described and claimed for carrying out the above stated objects and such other objects as will appear from the following description of certain preferred embodiments illustrated in the accompanying 40 drawings, wherein—

Fig. 1 is a side elevational view of a lock embodying the principles of the invention, certain parts thereof being shown in section and as applied to a stanchion of the type mentioned only certain fragmentary portions thereof being shown;

Fig. 2 is an enlarged sectional view taken on the line 2—2 of Fig. 1; and

Fig. 3 is a sectional view taken on the line 3—3 of Fig. 2.

Like characters of reference designate like parts in the several views.

In the drawings 5 represents the upper substantially horizontally relatively fixed member and 6 represents the upper end of

the laterally swingingly mounted member of the stanchion.

The member 5 is preferably tubular and is provided on its under side with a longitudinally extending slot 7. The member 5 60 is provided with a catch member which is preferably in the form of a collar 8 adjustably mounted thereon by screws 9. A transverse member, designated as a whole by the reference numeral 10, is mounted in and 65 adjacent the upper end of the swinging member 6. A latch member 11, substantially of the shape shown in Fig. 1, is loosely mounted on the transverse member 10, as will be hereinafter described, and is adapted 70 to slide in the slot 7 of the member 5 when the swinging member 6 is moved laterally.

A pair of outstanding ears or lugs 12 are provided on and adjacent the free end of the latch to limit downward movement thereof. 75 The lower portion of the collar 8 extends across the slot 7, as clearly shown in Fig. 1 and the free end of the latch is beveled at 13 so that the latch will easily ride over the catch when the swinging member 6 is moved 80 into its closed position. A pair of downwardly projecting lugs 14 are provided on the under side of the latch member which are adapted to bear against the respective sides of the catch, as clearly shown in Fig. 85 1, when the latch is in its locking position.

The transverse member 10 comprises a central rod member 15 on which a pair of spaced bushings 16 are mounted, the bushings being held in position by washers 17 90 bearing against the outer ends of the bushings and effectively held thereagainst by upsetting the extremities of the rod member 15, as shown at 18, see Fig. 2. The latch 11 is loosely mounted on the member 15. The 95 inner ends of the bushings bear against the respective sides of the latch. In the embodiment shown in Figs. 1 to 3 of the drawings, interlocking means are provided between the latch and the bushings, the latch 100 being provided on each side with a pair of lateral extending lugs 19 which are adapted to slip into suitable recesses 20 formed in the bushings 16, see particularly Fig. 3. By this arrangement it will clearly be apparent 105 that when the bushings are rotated in a counter-clockwise direction, the free end of the latch will be lifted out of engagement with the catch. To facilitate rotation of the bushings, hand wheels or disks 21 are mount-

ed on the outer ends thereof, and rigidly connected thereto by upsetting portions of the ends of the bushings into recesses 21 formed in the disks.

- 5 To prevent the latch from being jarred out of its locking position by the animal rubbing or pressing against the stanchion members, a spring 22 is preferably provided to hold the latch in locking engagement with 10 the catch. This spring is preferably coiled about the bushings 16, the end 23 thereof being fixed to the latch and the end 24 thereof being fixed to the stanchion member 6.

In order to guide the swingable stanchion member 6 on the horizontal portion of the fixed member 5 and to prevent strain due to the animal rubbing and pressing against the stanchion member from being transmitted to the latch member, the stanchion member 6 15 is preferably provided with a pair of up-standing arms 27 which are adapted to slidably engage the respective sides of the tubular member 5, see Fig. 2.

If desired, a plug 28 may be secured to the member 5 to limit outward movement of the swinging member 6, this plug cooperating with the lugs 12 provided on the free end of the latch and therefore prevents the latch from slipping entirely out of the slot 7. 30 From the foregoing description it will be apparent that an automatically operating lock of simple and strong construction has been provided which may be conveniently released from either side of the stanchion.

35 I claim:

1. In combination, a laterally swingingly mounted stanchion member, an upper horizontal fixed stanchion member, a catch on

said fixed member, a transverse member journaled in and adjacent the upper end of 40 said swinging member, a latch on said transverse member, said transverse member comprising a central member and a pair of bushings on said central member, said bushings being loosely mounted on said central member 45 so that their inner ends bear against the respective sides of said latch, and interlocking means on said latch and the inner ends of said bushing to insure lifting of the latch when said bushings are rotated in the proper 50 direction.

2. In combination, a laterally swingingly mounted stanchion member, an upper horizontal fixed tubular stanchion member, said tubular member having a longitudinally extending slot in its under side, a catch on said tubular member, a transverse member journaled in and adjacent the upper end of said swinging member, a latch on said transverse member and adapted to slide in said slot 55 and to slip into holding engagement with said catch when said swinging member is moved to closed position, said transverse member comprising a central member and a pair of bushings on said central member, 60 said bushings being loosely mounted on said central member so that their inner ends bear against the respective sides of said latch, and interlocking means on said latch and the inner ends of said bushings to insure 65 lifting of the latch when said bushings are rotated in the proper direction.

In testimony whereof, I affix my signature.

ROBERT MINSHULL.
